UNITED STATES PATENT OFFICE.

FRANK B. QUACKENBOSS AND JOHN A. NEALE, OF NASHVILLE, TENNESSEE.

ACCELERATOR.

Application filed June 7, 1921. Serial No. 475,730.

To all whom it may concern:

Be it known that we, FRANK B. QUACKENBOSS and JOHN A. NEALE, both citizens of the United States, and residents of Nashville, 5 in the county of Davidson and State of Tennessee, have invented certain new and useful Improvements in Accelerators, of which the following is a specification.

This invention relates to an accelerator 10 for dry pipe valves.

As is well known, dry pipe valves are used principally in connection with automatic fire extinguishers, such as the sprinkler type, said valves operating in conjunction with 15 compressed air, the pressure of air maintaining the valve in its closed position, and whenever the air decreases to a predetermined degree the valve is opened.

The object of the present invention is to 20 provide a device by which the opening of the dry pipe valve may be accelerated or quickened simultaneously with the decrease of air pressure.

It is also an object of the invention that 25 the accelerator be positive and reliable in its operation.

Other objects and objects relating to details of construction, combination and arrangement of parts will hereinafter appear 30 in the detailed description to follow.

The invention is illustrated by way of example in the accompanying drawings, in which:

Figure 1 is a diagrammatic view showing 35 our invention when applied,

Figure 2 is a longitudinal vertical section of the accelerator,

Figure 3 is a plan view of the same with the top removed.

Referring to the drawings more particularly, 40 10 indicates generally a dry pipe valve to one end of which there is connected an outlet pipe 10 and the other end an inlet pipe 11. The outlet pipe 10 is in turn connected with a plurality of inter-communicating pipes which form a fire extinguishing system and the pipe 11 is connected with a suitable source of water supply. In the pipe 10 there is maintained a predetermined air

50 pressure by which means the valve A is enabled to retain a closure between the pipes 10 and 11.

In order to accelerate the opening of the valve A when the pressure in the pipe 10 decreases, we provide a tank as generally in-

dicated at 12 and which may be suitably supported in the position shown in Figure 1. A suitable cover 13 is provided for the tank, and also said tank is reduced in cross section at its lower end as shown at 14.

A partition wall 15 is formed with the tank dividing the same into two chambers 17 and 18, and said partition wall having its lower end in spaced relation with the bottom of the tank, as shown at 16. Also this 60 wall is formed with a miniature orifice as shown at 19. With the chamber 17 there communicates an induction pipe 20 and an ejection pipe 21. The pipe 20 communicates with the pipe 10, while the pipe 21 is 70 extended by the sections as indicated at 22, and said sections in turn communicating with the atmosphere through the L-fitting 23. Formed on the interior of the chambers 17 and in alignment with the pipe 21 is a 75 short tubular extension 24. At the outer side of the compartment 17 there is journaled in its side walls a shaft 25 upon which there is secured a pair of collars 26, said collars being each formed with an extension 80 arm 27. The extension arms 27 are bent downwardly as at 28, and at their outer ends secured to a float member 29. Between the arms 27 near their pivoted ends there extends a cross member 30, said member in 85 turn carrying on its lower face a washer as indicated at 31. When the arms 27 are lowered as shown in Figure 2, said washer is adapted to close the outlet pipe 21.

Within the tank 14 there is placed a quantity 90 of mercury as shown at 32. The mercury may pass between the chambers 17 and 18 beneath the division wall 15, and is sufficient in quantity to normally permit the float 29 to remain in position for closing the outlet 95 pipe 21. That is, the float will remain in this position as long as the pressure existing in the chambers 17 and 18 are equal.

The operation of the present device is as follows: When the system of pipes which 100 inter-communicate with the pipe 10 are ruptured, and air pressure in the pipe 10 is destroyed, or otherwise the air pressure in the pipe 10 begins to decrease, and then the existing pressure in the chamber 17 will 105 likewise decrease. The decrease of pressure in the chamber 17 will naturally become very rapid and due to the fact that the orifice 19 forms the only communication between this chamber 17 and 18, the pressure 110

in the chamber 18 cannot equalize itself with a rapid fall of pressure in the chamber 17. The pressure in the chamber 18 then being the greatest the mercury therein will be partly drawn into chamber 17 and hence the float 29 will be raised, which in turn will open the pipe 21. The pipe 21 being in communication with the atmosphere will permit the direct communication of the pipe 10 with the atmosphere, and in this way the decrease of pressure in the pipe 10 will be quickened or accelerated, and thereby the opening of the valve A to permit water to flow into the pipe 10 will likewise be quickened or accelerated.

While we have shown the preferred form of our invention, we wish it to be understood that we are aware of the fact that the general construction, combination and arrangement of parts might be changed by those skilled in the art without departing from the spirit of our invention, as indicated by the appended claims.

We claim:

25. 1. An accelerator of the class described comprising in combination, a closed tank, a division wall for dividing said tank into two compartments, said division wall being arranged to terminate in spaced relation 30 with the bottom of said tank, and said division wall having a restricted orifice adjacent its upper end, a body of liquid within the tank and the level of said liquid being above the lower end of the division wall 35 and one of said compartments being provided with an inlet and an outlet, said inlet being connected to a supply of compressed air and said outlet communicating with the atmosphere, a valve for said outlet 40 adapted to normally close the same, and means for opening said valve when air

pressure in the two compartments becomes unbalanced.

2. An accelerator of the class described, comprising in combination, a closed tank, a division wall therefor, having a restricted passage in its upper end and having its lower end in spaced relation with the bottom of the tank, an inlet and an outlet for one of said chambers, said inlet communicating with a compressed air supply and said outlet communicating with the atmosphere, a quantity of liquid in the bottom of the tank adapted to cover the lower end of the division wall, a valve adapted to normally close the outlet communicating with the atmosphere, and float means adapted to operate said valve for opening the pipe communicating with the atmosphere when the air pressure in the two chambers becomes unbalanced.

3. In an accelerator of the class described, comprising in combination, a closed tank, a division wall therefor dividing said tank into two compartments, said division wall having an orifice formed near its upper end, and a passage at its lower end by which the bottoms of the two chambers are in communication, an inlet and outlet for one of said chambers, said inlet communicating with a source of compressed air and said outlet communicating with the atmosphere, a flap valve adapted to normally close the outlet, a quantity of liquid in the bottom of the tank adapted to seal the passage between the two chambers, and float means by which the flap valve may be raised, and by which the flap valve may be lifted when the air pressure in the chambers becomes unbalanced.

FRANK B. QUACKENBOSS.
JOHN A. NEALE.
